UNITED STATES PATENT OFFICE

LAURENCE E. POWER, OF MILWAUKEE, WISCONSIN, ASSIGNOR, BY MESNE ASSIGNMENTS, OF ONE-HALF TO LYNDE BRADLEY AND ONE-HALF TO HARRY L. BRADLEY, BOTH OF MILWAUKEE, WISCONSIN

RESISTOR UNIT AND METHOD OF FORMING THE SAME

Application filed June 10, 1927. Serial No. 197,882.

One difficulty experienced in connection with resistor units when used in circuits where it is of vital importance that their resistance value remain constant, is that being of a more or less porous nature they absorb considerable moisture from the surrounding atmosphere as a result of which their conductivity values vary according to the condition of the surrounding atmosphere and this invention has as an object the provision of improved resistor units which are impervious to moisture to thus prevent changes in their conductivity values irrespective of the surrounding atmospheric conditions.

Another object of this invention resides in the provision of an improved method of forming resistor units whereby the units are rendered moisture-proof to prevent the entrance of the moisture in the pores thereof.

It is a further object of this invention to provide an improved resistor unit of the character described having an outer wrapping or tube of fibre or paper enclosing the exposed portions of the resistance material to, with the end terminals or caps, completely enclose the resistance material and prevent its contact with the atmosphere.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated several complete examples of the physical embodiment of my invention constructed according to the best modes I have so far devised for the practical application of the principles thereof, and in which:

Figure 1 is a view in side elevation and in perspective of the resistance body and the wrapping, therefor, respectively;

Figure 2 is a side view, partly in section and partly in elevation, illustrating one of

the resistor units prior to the application of the last end cap or terminal;

Figure 3 is a side view, with parts broken away, illustrating the first step in subjecting the completed unit to a coating of paraffin or other moisture-proofing material;

Figure 4 is a side view illustrating the manner of evacuating the air from the unit pores while the units are immersed in the water-proofing material;

Figure 5 is a side view, with parts broken away, of a completed unit of a slightly modified construction, and

Figure 6 is a side view of a completed resistor unit with the end terminals or caps eliminated.

Referring now more particularly to the accompanying drawings, in which like numerals designate like parts throughout the several views, the numeral 10 designates a body of resistance material formed in accordance with my copending application Serial No. 197,881, or in any other desirable manner and adapted to have a constant resistance of a predetermined value, end caps 70 or terminals 11 of suitable design being secured over the ends of body 10 to provide means for connecting the unit in an electric circuit. The terminals 11 are preferably pressed over the ends of the body 10 after it has been formed and have a permanent fit thereon.

Due to the critical operation of radio receiver circuits in which resistor units of this type are especially adapted. It is of utmost importance that every possible safeguard be provided to prevent variations in the conductivity of the unit. The body 10 being of a more or less porous nature has a tendency to absorb moisture, the effect of which is to change its conductivity and this objectionable feature is overcome by shielding all exposed surfaces of the unit from the atmosphere by the terminals 11 at its ends and a tube or wrapping 12 at its intermediate portion, the ends of the tube or wrapping having a snug engagement with the adjacent terminal whereby the resistance body is entirely enclosed.

I further protect the units from moisture

by first immersing the completed units in a high grade paraffin or other water-proofing material 13 having a high melting point of approximately 58 to 60 degrees centigrade.

- 5 The units are placed on a tray or other support 14 and placed in a container 15 filled with paraffin which is melted by heat from a burner or other means 16. The container 15 with the units therein is then placed with-
 10 in a vessel 17 from which the air is evacuated through a tube 18, as a result of which the air within the pores of the units is extracted. The vacuum within the vessel 17 is then released after a predetermined period of time
 15 and the melted paraffin or other water-proofing material enters the pores of the unit, thoroughly providing for the exclusion of moisture. The units are then removed from the paraffin which congeals leaving a coat-
 20 ing 19 thereon.

If desired, the end terminal members 11 may be dispensed with as disclosed in my copending application, Serial No. 197,881, in which case the ends 20 of the resistance unit
 25 are tapered to provide means facilitating engagement with a suitable mounting.

From the foregoing description taken in connection with the accompanying drawings, it will be readily apparent to those skilled in the art to which an invention of the character described appertains that I provide an improved resistor unit and method of forming the same whereby the units are rendered substantially moisture-
 35 proof.

What I claim as my invention is:

1. The herein-described method of forming resistor units which consists in molding a body of resistor material, in encasing the
 40 body, the ends of the casing terminating short of the ends of the unit, and in pressing terminal members on the ends of the body to bear against the ends of the casing, the terminals and casing providing a substantially atmospherically tight enclosure for the unit to protect the same.

2. The herein-described method of forming resistor units which consists in molding a body of resistor material, in encasing the
 50 body, the ends of the casing terminating short of the ends of the unit, in pressing terminal members on the ends of the body to bear against the ends of the casing, the terminals and casing providing a substantially atmospherically tight enclosure for the unit to protect the same, and in coating the assembled unit with a water proof material.

3. The herein-described method of forming resistor units which consists in providing a body of resistance material, in encasing the body with the ends of the casing terminating inwardly of the ends of the body, in pressing terminals on the ends
 65 of the body to bear against the ends of

the casing to enclose the body and protect the same against the atmosphere, and in coating the assembled unit with a water-proofing material in an evacuated vessel.

4. The herein-described method of forming resistor units which consists in providing a body of resistance material, in encasing the body with the ends of the casing terminating inwardly of the body, in pressing terminal members on the ends of the body to bear against the ends of the casing to enclose the body and protect the same against the atmosphere, in immersing the assembled unit in molten paraffin, in placing the unit while immersed in paraffin in an evacuated vessel to open the pores of the casing, and in allowing air to enter the vessel to force the paraffin into the open pores of the casing to thoroughly impregnate the same.

5. A resistor unit, comprising a molded resistance body of uniform shape and dimensions throughout its length, an encasing member having internal dimensions and shape conforming with the shape of the molded body in transverse section and adapted to be engaged over said body to enclose the intermediate portion thereof and having a snug fit thereon with its ends terminating short of the adjacent ends of said body, and terminal members having exterior dimensions approximating that of the encasing member and internal bores of shapes and dimensions to receive the ends of the molded body with the inner marginal edges of the terminal members abutting the ends of the encasing member to, with the encasing member, provide an enclosing shield for the resistance body.

6. A resistor unit, comprising a molded resistance body of uniform shape and dimensions throughout its length, an encasing member having internal dimensions and shape conforming with the shape of the molded body in transverse section and adapted to be engaged over said body to enclose the intermediate portion thereof and having a snug fit thereon with its ends terminating short of the adjacent ends of said body, terminal members having exterior dimensions approximating that of the encasing member and internal bores of shapes and dimensions to receive the ends of the molded body with the inner marginal edges of the terminal members abutting the ends of the encasing member to, with the encasing member, provide an enclosing shield for the resistance body, and a coat of water-proof material for preventing leakage of moisture through the encasing member.

In testimony whereof I hereunto affix my signature.

LAURENCE E. POWER.
